WATER SEAL FOR PUMPS

William Hogan, Augusta, Ga., assignor to Georgia
Iron Works, Augusta, Ga., a corporation of
Georgia

Application October 13, 1939, Serial No. 299,383

2 Claims. (Cl. 286—7)

This invention relates to the art of fluid pumps and particularly to centrifugal pumps designed for handling liquids or liquids containing or conveying solids.

Although not restricted thereto, the invention finds an improved field of use in sand pumps for dredging operations and the like. In centrifugal pumps employed for such operations considerable difficulty is encountered in maintaining a proper seal in order to prevent recirculation of material in the pump. Such recirculation materially lowers the efficiency of the pump.

An object of this invention is to provide an improved seal for preventing recirculation in centrifugal pumps and the like.

Another object is to provide an improved construction of liquid seal between the impeller of a centrifugal pump and its adjacent face plates.

A further object is to provide in a centrifugal pump, a novel construction of seal ring and manner of mounting the same.

Other objects will be readily apparent to those skilled in the art. While the present disclosure constitutes a preferred embodiment by which the invention is reduced to practice, it is to be understood that within the scope of the invention as claimed any desired variations and changes may be made in the structural details.

In the accompanying drawing, wherein like characters designate like parts throughout the several views:

Figure 1 is a central vertical section through the centrifugal pump equipped with a seal in accordance with the invention.

Figure 2 is an enlarged fragmentary section illustrating the seal mounting detail of Figure 1.

Figure 3 is a fragmentary perspective of an inner seal ring employed in the pump.

Figure 4 is a fragmentary perspective view of an outer seal ring, also used.

Figure 5 is a central vertical section through a pump and illustrating the disposition of sealing means on both the suction side and the hub side of the pump.

In detail the pump comprises a volute shell 6 within which is disposed an impeller 7 mounted on the end of the pump shaft 8 which has a bearing in the hub side plate 9. The suction side of the pump casing is closed in the usual manner by the suction side face plate 10 which is centrally apertured to provide the suction inlet 11 for the pump, the inlet being co-axial with the pump shaft.

On its suction side the impeller 7 has rigidly

secured thereto, as by bolts 12 or by welding, a peripherally stepped annular plate 13 which rotates with the impeller within the annular chamber 14 formed in the suction side face plate 10.

5 Approximately in axial alignment with the outer step 15 of the runner plate 13, the suction face plate 10 is formed with an undercut annular groove 16 which receives the base flange of a rubber sealing ring 17. The ring 17 has a snap action in its engagement with the seating groove 16 and it is securely retained in position by means of a metal lock ring 18. The lock ring 18 is snapped in place inside the rubber ring and seats upon the ledge formed by the outer wall 15 of the groove 16. The outer peripheral face of the ring is tapered with respect to the seal ring 17, so that when the ring 18 is snapped in place the base of the sealing ring is wedged radially into the seating groove 16 and is thus firmly 10 anchored in position on the hub side face plate 10. The rubber sealing ring 17 extends inwardly over the periphery of the outer step 15 on the runner plate and has an internal bead 19 which bears against the periphery of the step under the tension imparted by the resiliency of the ring.

The inner step 20 of the runner plate 13 is chamfered as at 21 along its outer peripheral edge. The chamfered portion lies beneath an inner sealing ring 22, also of rubber, and which, like the outer seal ring 17, has a base flange which seats in an undercut groove 23 formed in the suction side face plate 10. The inner seal ring 22 has a relatively thick base portion and its outer peripheral face is tapered inwardly in the direction of the runner plate 13. The free end of the ring bears against the cylindrical periphery of the step 20, and the ring is anchored at its base by a retaining ring 24 which is reversely 20 tapered with respect to the periphery of the base of the seal ring and which is snapped over the base of the seal ring to wedge the same firmly into the undercut groove 23. It will be apparent that by means of the snap rings 18 and 24 25 the outer seal ring and the inner seal ring are both firmly secured in position upon the suction side of the face plate of the pump and they are assembled on this plate before it is applied in position. This construction eliminates the necessity for the use of headed or screw threaded fastening elements as a means of anchoring the sealing rings in place.

While the outer and inner steps 15 and 20, respectively, are shown as being provided by the 30 plate 13 which is attached to the impeller,

these steps may be cast as integral portions of the impeller, if desired.

Figure 5 illustrates the construction of sealing ring assembly which is disposed both at the suction side and at the hub side of the pump. In order to prevent unnecessary repetition, and in view of the fact that details of sealing rings and retaining rings are identical at each side of the pump, the same reference characters have been employed to indicate identical parts at each side, the only difference being that at the respective sides of the pump the elements are reversed in position.

The wall of the face plate 10 is provided with an aperture 25 through which water or other liquid is supplied under pressure to the sealing chamber 14. The pressure at which the sealing medium is supplied to the chamber 14 is held at a higher point than the pressure existing within the pump. This results in a slight lifting of the outer seal ring bead 19 which permits the sealing liquid, generally water, to flow beneath the bead and lubricate its bearing on the step 15. The inner seal ring 22 is provided with an annular series of bleeder passages 26 through which the sealing liquid from the chamber 14 is permitted to pass in small volume so that it becomes effective in lubricating the bearing between the ring 22 and the step 20 of the runner plate.

As in all such pumps, a definite clearance space 27 exists between the impeller 7 and the suction side face plate 10. A similar clearance space 28 exists between the impeller and the hub side face plate 9. As there is a high pressure in the volute 6 and a relatively lower pressure at the inlet 11, at which a definite suction exists, there is a constant tendency for the material which the pump is handling to be forced back from the volute through the clearances 27 and 28 to the axial area of the impeller and thus to be recirculated with the consequent lowering of pump efficiency. In the present invention the higher pressure maintained within the chamber 14 insures against collapse of the outer sealing ring 17 so that this ring effectively blocks off any passage of pump material radially inward along the passage between the impeller and the adjacent base plate. At the same time the chamber pressure maintains the ring 22 in sealing contact with the runner step 20 and only a small

portion of the sealing liquid is allowed to pass through the bleeder passages 26. This small volume of the sealing liquid is adequate to maintain lubrication. The chamfered portion 21 of the step 20 of the runner plate 13 eliminates any possibility of the ring 22 becoming pinched between the runner plate and the side face of the pump shell.

An important feature of the invention resides in the fact that the contacting faces of the outer sealing ring 17 and its retaining ring 18 are reversely tapered as are also the contacting faces of the inner sealing ring 22 and its retaining ring 24. This tapering results in a definite wedging action which crowds the base of each ring radially into its undercut holding groove. No projecting parts are exposed and the entire assembly is of simple rugged construction.

I claim:

- 20 1. In a centrifugal pump, a face plate having an axial recess open to the inner side thereof, an undercut annular groove in a wall of the recess, a rubber sealing ring having a base flange seated in the groove, a resilient retaining ring overlying and in pressure engagement with the sealing ring in radial alignment with its base flange, and the contacting face of the retaining ring being beveled inwardly toward the sealing ring from the outer to the inner side faces of the retaining ring whereby to wedge the base flange of the sealing ring radially into its groove, said resilient retaining ring constituting the sole means for holding said sealing ring in place.
- 25 2. In a centrifugal pump, a face plate having an axial recess opening to the inner side thereof, an undercut annular groove in a wall of the recess, a rubber sealing ring having a base flange seated in the groove, said ring having its surface opposite to the base flange beveled from the base of the ring away from the opposite flange bearing side of the ring, a resilient retaining ring overlying and in pressure engagement with the sealing ring in radial alignment with its base flange, and the contacting face of the retaining ring being reversely beveled with respect to the surface of the sealing ring whereby to wedge the base flange of the sealing ring radially into its groove, said resilient retaining ring constituting the sole means for holding said sealing ring in place.

WILLIAM HOGAN.
